UNITED STATES PATENT OFFICE.

EMELINE CLARK POST, OF YORKTOWN, VIRGINIA.

DESIGN FOR A THERAPEUTIC BOTTLE.

SPECIFICATION forming part of Design No. 18,879, dated January 22, 1889.

Application filed December 4, 1888. Serial No. 292,668. Term of patent 7 years.

To all whom it may concern:

Be it known that I, EMELINE CLARK POST, a citizen of the United States, residing at Yorktown, in the county of York and State of Virginia, have invented a new and useful Design for a Therapeutic Bottle, of which the following is a specification:

My invention relates to a design for a therapeutic bottle; and it consists in a certain new and original configuration, fully described hereinafter in connection with the accompanying drawings, wherein—

Figure 1 is a perspective view of the appliance, made in accordance with my invention. 15 Fig. 2 is a transverse sectional view of the same on the line $\alpha-\alpha$ of Fig. 3. Fig. 3 is a longitudinal sectional view.

In reference to the drawings, A designates the crescent-shaped body of the bottle, having a flat vertical inner side, a, and a semi-elliptical outer side, a', the upper and lower edges of the outer side joining the corresponding edges of the inner side. The broadest portion of the body is at its center, from which 25 point the body tapers gradually toward the

extremities of the horns B B, at which points the outer side meets the inner side to form edges or points. Knobs C C are arranged on the inner side near the rear extremities of the horns, and buttons D D are arranged on the outer side near the rear extremities of the horns. An outlet tube or projection, E, is provided on the outer side of the body at its center.

Having thus described the invention, I 35 claim—

The design for a therapeutic bottle, consisting of the crescent-shaped body A, having a flat inner side and a semi-elliptical outer side, the horns B B of the said body being tapered 40 toward their extremities, substantially as shown.

In testimony that I claim the foregoing as my own I have hereto affixed my signature in presence of two witnesses.

EMELINE CLARK POST.
